UNITED STATES PATENT OFFICE.

EDMUND R. WARE, OF WORCESTER, MASSACHUSETTS.

GRINDING AND POLISHING MACHINE.

SPECIFICATION forming part of Letters Patent No. 289,323, dated November 27, 1883.

Application filed March 21, 1883. (No model.)

To all whom it may concern:

Be it known that I, EDMUND R. WARE, a citizen of the United States, residing at Worcester, in the county of Worcester and State 5 of Massachusetts, have invented certain new and useful Improvements in Grinding and Polishing-Machines, of which the following is a specification, reference being had therein to the accompanying drawings.

10 Figure 1 is a perspective view of a machine embodying my invention. Fig. 2 is a top or plan view of the chuck employed for holding and presenting the article to be ground or polished, together with the ways upon which the 15 chuck moves. Fig. 3 is an elevation, partly in section, taken on line $x-x$, Fig. 2.

Referring to the drawings, A A represents the frame-work, which supports the operative parts of the machine, and B is a bed- 20 plate provided in Fig. 1 with a lateral extension, B', the extension having upon its upper face ways or grooves adapted to be traversed by the base-plate of the chuck, to be hereinafter described.

25 C C are vertical posts arranged upon the opposite sides of the machine, and about midway between the corner lugs or posts of the frame.

D D E E e constitute a frame mounted to 30 slide vertically upon the posts C C when actuated by certain devices, to be hereinafter described. By preference, I bolt a rabbeted or flanged rib, D, to each of the opposite posts C, the ribs being of suitable form in cross- 35 section to provide grooves between their inner edges and the posts for the reception of the vertical side bars of the frame.

F is an emery-wheel shaft mounted in bearings a b d, which project horizontally from the 40 sliding frame, the shaft being stepped upon and adjusted by a set-screw, f, in the lower end of the lower bearings, a.

G is an emery-wheel or other suitable polishing or grinding wheel mounted upon and 45 carried by the upper end of shaft F, to which a rapid rotary motion is given by means of a belt connecting a belt-pulley, g, on the shaft with any suitable motor. The pulley g is splined to shaft F, and has a downwardly-projecting neck or sleeve, which is seated in the 50 inner end of a bracket or supporting-arm, D',

which is attached to one of the posts C. In practice, I usually prefer to make the bracket and bearing in two parts, bolted together, as indicated in the drawings.

H is a driving-shaft mounted in bearings c, which project from the posts C, the shaft being driven by a pulley, h, and belt, not shown.

I is a vertical shaft mounted upon the frame A A in suitable bearings, and carrying a worm-wheel, i, which is actuated by a worm on the driving-shaft H, but not shown.

J is a grooved cam mounted on vertical shaft I, and secured thereto by a set-screw, (see Fig. 4,) or otherwise.

j is a stud projecting from the vertical bar e of the sliding frame, and entering the groove of the cam, the stud by preference being provided with an anti-friction roller.

By means of the mechanism thus described 70 a rapid rotary motion and also a rising-and-falling motion may be imparted to the shaft F and the emery-wheel or other grinding or polishing wheel mounted thereon, as will be readily understood from an examination of 75 Figs. 1 and 4 without further explanation.

I will now proceed to describe various mechanisms which I have invented for properly supporting and presenting to the grinding-wheel the article to be ground or polished.

Referring to Figs. 1, 2, and 3, B' is an extension or continuation of the upper plate, B, of the main frame, and is provided with grooved or ribbed ways, upon or between which slides a base-plate, K.

k is a drum or short section of a cylinder provided upon its lower edge with an external beveled gear, and arranged to fit closely over a circular boss formed for its reception on the upper face of the sliding base-plate K, the drum being further secured in its position by a central stud or pivot, o, (see Fig. 3,) around which, as a center, the drum vibrates or rotates.

K' is a shaft mounted upon the lower face 95 of the extension B', and carrying a pinion, k, which meshes with a cogged rack on the under side of the sliding plate K.

K² is a hand-wheel on the outer end of shaft K', by means of which the sliding plate can 100 be moved toward or from the grinding-wheel shaft F at the will of the operator, the rela-

tion of parts being such that the central pivot, o , travels toward and from said grinding-wheel shaft on a line which is radial to said shaft and to the grinding-wheel G.

5 O is a shaft mounted in an arm, K³, which projects horizontally from the sliding base-plate K, and has a rotary motion imparted to it by a belt passing around pulley O', and thence to any desired motor, which should be placed, by preference, above the machine, and at such distance as to permit the base-plate and the appliances mounted thereon to move toward and from the grinding-wheel, as may be needed without unduly affecting the tension of the belt.

O' is a shipping-lever pivoted to the arm K³, and carrying at its short end a fork, which engages with a clutch, o², whereby the belt-pulley may be connected to the shaft O, or disconnected therefrom, as may be required. Shaft O carries at its inner end a bevel-pinion, which meshes with the bevel-gear on the lower edge of drum k, (see Figs. 1 and 3,) whereby a rotary motion may be imparted to said drum and 25 to appliances connected therewith, as follows:

L is an upper plate, and L' a lower plate, the latter being made fast directly to the drum k. The upper plate is connected with the lower one by a series of studs or bolts, o' o', which 30 serve as pivots for the swinging arms N M, and also by means of an outer series of studs or bolts, n. (See Fig. 1.) The two parts N M of the swinging arms are connected together by tongues and grooves, preferably dovetailed, 35 so that the parts M can slide longitudinally upon the parts N, and are secured in their position after adjustment by set-screws or other analogous devices. Each arm carries at its outer end a sharp-pointed set-screw, m. The 40 upper plate, L, is provided near its outer edge with four circular slots, ll, each of which is concentric with the pivot o' of its respective swinging bar, each bar carrying also an adjusting binding-screw arranged to traverse the circular slot, whereby said arm may be securely fastened at such angle relative to the pivot o as it may be placed in, its vibration in a horizontal plane being limited only by reason of its binding-screw engaging with the walls of 45 the plate L at the ends of its slot l. These last-described devices constitute, therefore, a sort of chuck, which is designed more especially to receive and support irregular-shaped articles—such as, for instance, the base-plates 50 of stoves—which have narrow downwardly-projecting flanges around their outer edges; and it will be readily understood that these swinging extensible arms can be readily adjusted in such manner as to receive and properly support a stove base-plate, even though the same be of very irregular outline; and it will also be seen that when thus supported such stove-plate can be advanced toward and pressed against the grinding-wheel G upon a 55 line which is radial to said wheel and to its supporting-shaft F, the stove-plate meantime

having imparted to it a rotary motion, and being held in contact with the grinding-wheel by means of the hand-wheel K² and the rack and pinion operated thereby.

70

My machine may be operated as follows: The article to be ground—say, for instance, an irregular-shaped base-plate for a stove—being secured upon the chuck, a slow rotary motion is imparted to said chuck and plate, both of 75 which are advanced by means of hand-wheel K², so as to keep the edge of the plate pressed against the rapidly-revolving grinding-wheel. When turning sharp corners, the plate should be withdrawn from contact with the wheel, to 80 prevent improperly cutting such corners to a greater angle from the plane of the upper face of the plate than other portions of the edge are cut.

What I claim is—

85

1. In a grinding and polishing machine, the combination of the following elements, namely: a grinding-wheel, a sliding carrier-frame, a carrier rotating about an axis which is parallel with the axis of the grinding-wheel, mechanism mounted on the sliding carrier-frame for rotating the carrier, and mechanism adapted to be operated by the attendant for advancing the article being ground toward the grinding-wheel and withdrawing therefrom when 95 turning corners, substantially as set forth.

90

2. In a grinding and polishing machine, the combination of the following elements, namely: a grinding-wheel, a sliding carrier-frame, a rotating carrier supported wholly from one 100 side upon a pivot mounted on the sliding carrier-frame and parallel with the shaft of the grinding-wheel, a driving-shaft mounted on the sliding carrier-frame at a right angle to the grinding-wheel shaft, and gearing connecting the driving-shaft with the rotating carrier, substantially as set forth.

105

3. In a grinding and polishing machine, the combination, with the grinding-wheel and the sliding carrier-frame, of the carrier mounted 110 on the sliding frame and supported wholly from below, the driving-shaft and gearing for rotating the carrier, the hand-wheel mounted on the outer end of shaft K', the clutch connecting the band-wheel with the driving-shaft, 115 and the shipping-lever mounted on the sliding frame and extending beneath the plane of the carrier to within reach of the operator at the hand-wheel, substantially as set forth.

115

4. In a grinding and polishing machine, the 120 combination of a tapering grinding-wheel and a carrier whose axis of rotation is parallel with the shaft of the grinding-wheel, and is movable on a line which intersects the shaft of the grinding-wheel, substantially as set forth.

125

5. In a grinding and polishing machine, the combination of a tapering grinding-wheel and a carrier which rotates in a plane at right angles to the grinding-wheel shaft, and is movable on a line intersecting the shaft of the grinding-wheel.

130

6. In a grinding and polishing machine, the

combination of pivoted arms and extensible arms attached to and movable relatively to said pivoted arms, substantially as set forth.

7. In a grinding and polishing machine, the combination of a series of pivoted arms and means for securing said arms in such positions as they may be adjusted to, substantially as set forth.

8. In a grinding and polishing machine, a series of longitudinally-extensible arms, in combination with movable points or dogs secured to the outer ends of said arms, substantially as set forth.

9. In a grinding and polishing machine, a mechanism for holding the article to be ground, 15 consisting of two substantially-parallel plates mounted upon and adapted to rotate about a central pivot, and a series of arms pivoted between said plates, substantially as set forth.

In testimony whereof I affix my signature in 20 presence of two witnesses.

EDMUND R. WARE.
